DRILLING DEEP HOLES IN WOOD

John William Stolle, Danbury, Conn., assignor to
Charles W. Stevens, Danbury, Conn.

Application June 20, 1936, Serial No. 86,244

7 Claims. (Cl. 144—309)

This invention relates to the woodworking art, and particularly to the formation of holes in textile spools and bobbin blanks and the like, and particularly to the drilling of straight deep holes having sections of different diameter in elongated blanks by the use of relatively slender and flexible drills.

In the drilling of these blanks according to conventional practice there is a very substantial waste and loss of material due, among other things, to the long slender drill or boring tool being deflected from its rectilinear path by the grain of the wood which is not always parallel to the hole to be driven. This difficulty may be largely obviated by the use of the invention of my Patent No. 1,513,350, issued October 28, 1924, which comprises the use of a drill having a special cutting and shaving edge and a stream of liquid, such as water or oil, to wash out the chips which are formed during the drilling operation, and to moisten and soften the wood to be bored. While the liquid step is satisfactory in some branches of the wood boring art, such as the boring of hook handles, whiffletrees, wood machine rolls, etc., I have found that in the drilling of textile spools and bobbin blanks that the oil or soap water employed has a deleterious effect upon the wood.

One object of the invention, therefore, is the provision of means for utilizing compressed air and the like to blow out the chips and cuttings during the boring operation, together with the provision of a special drill which, in addition to the patented features of my Patent 1,513,350, embodies features particularly adapted to the use of compressed air and capable of forming a hole in a manner which is self directing and guiding along a straight rectilinear path, notwithstanding the non-parallelism of the wood grains.

A further object of the invention is the formation of a hole having sections of different diameter through a wooden blank, as for example a blank having an elongated hole of three different cross-sections, by first, and in one operation, drilling a hole equal to the desired diameter of the middle section of the blank and then in another single operation continuing the hole at a smaller diameter through to the end and reaming out the other end and by the use of a drill which does not rub against the walls of the intermediate hole previously formed.

A further object of the invention is a drill of the above indicated character which leaves an uncut core of wood in the center of the blank surrounded by a cylindrical guiding groove for as-

suring the straight rectilinear progress of the drill through the blank, notwithstanding the fibrous character of the wood.

A further object of the invention is a novel and improved form of machine for drilling and boring wooden blanks of the above indicated character.

For a better understanding of the invention, reference may be had to the accompanying drawings forming a part of this application wherein:

Figs. 1 to 5 inclusive are diagrammatic views illustrating steps in the drilling of a blank according to the invention;

Fig. 3a is an enlarged sectional view showing the cylindrical central guiding core and the surrounding cylindrical guiding groove formed at the bottom of the bore.

Fig. 6 is a plan view substantially enlarged of the end of the drill;

Fig. 7 is an end view thereof;

20

Fig. 8 is a side view of the machine;

Fig. 9 is a plan view of the machine;

Fig. 10 is a side view showing a step in the operation of the machine;

Fig. 11 is a sectional view along the line 11—11 of Fig. 8; and

Fig. 12 is a detail view of certain parts of the machine.

Referring to Figs. 1 to 5, I have indicated at 1 a textile bobbin blank or the like to be drilled and at 2 a drill according to the present invention for drilling and forming a hole 3 of the desired diameter in the middle section of the blank. This drill 2 forms the bore 3 to the point 3' where it is desired to discontinue the bore of that section.

At 4 I have shown a drill which continues the bore throughout the blank to form a bored section 5 at one end and simultaneously therewith to ream out a section 6 of a still larger bore at the other end; the completed drilling operation being indicated in the blank of Fig. 5. The multiple section bore 3, 5 and 6 of the blank is formed in two operations, the drill 2 forming the bore indicated in Figs. 2 and 3 and the drill 4 forming the bore 5 and 6 of Fig. 5. Fig. 4 shows the second drilling operation. The shank 7 of the drill 4 is of smaller diameter than the intermediate bore 3 of the blank.

I have found that by drilling the hole in the two operations by the two drills 2 and 4, that the tendency of the drill to be deflected from a rectilinear path during the relative longitudinal and rotational movements of the blank and the drill is substantially reduced. I believe this due to re-

duction in vibrations of the long slender drill which are present when a single drill is utilized for drilling simultaneously both larger and smaller bore sections, namely, when the drill is engaging the wood at two or more widely separated points longitudinally of the blank. According to one aspect of the invention the drill 2 is utilized for forming the intermediate bore 3, while the drill 4 is utilized for forming the end bores 5 and 6. The reaming part 8 of the drill 4 for forming the enlarged bore end 6 does not come into operation until the bore 5 is on its way to completion and, accordingly, the drilling operation of the two ends of the blank at this stage does not produce the same tendency to deflection as when the two operations occur at points closer to the middle section. By having the shank 7 of a smaller diameter than the bore 3 the rubbing of the shank against the walls of the bore 3 is prevented, thus removing any danger of vibration from the tip 9 of the drill, while it completes the bore 5.

For disposing of the chips and cuttings as the drill progresses, I supply fluid gaseous pressure, such as air, through the passages 10, 10' formed longitudinally of the drills. This passage or channel 10 (10') passes down through the tip 9 of the drill and the compressed air or other gaseous fluid blows the chips and cuttings backwardly along the drill, namely, along the groove 11 which is formed in the side of the drill.

As a further means for obviating deflection of the long slender drill from a straight rectilinear path, notwithstanding the departure from parallelism of the wood grain, I have provided a drill tip 9 formed generally as indicated in Figs. 1 to 4, and as more specifically illustrated in Figs. 6 and 7. This improvement consists of forming the tip 9 of the drill so that it will form in advance of the bores 3 and 5 an annular groove 15 which approaches the cylindrical form with an uncut core 16 surrounded by the annular groove 15 and disposed in the axes of the bores. For this purpose I have provided the tip 9 of the drill with a relatively short pilot cutting section 17 eccentric to or offset from the axis 18 of the drill and bores. This pilot section 17 is of lesser diameter than the main body tip 9 and forms the groove 15 and the core 16 in advance of and in alignment with the bores 3 and 5. The pilot section is formed on the advancing edge 17' of the drill, that is, relatively to the blank 1 and it may be milled or ground at 19 to form the cutting edge 20. The drill is provided with a cutting and reaming side edge 21 (preferably formed by milling or grinding, as indicated at 21') of my patent above referred to. Thus, two reaming edges 20, 21 and three boring edges 17, 17' and 22 are provided, the edges 17, 17' of the pilot section forming a salient. The groove 11 in the side of the drill should be deep enough to accommodate the uncut core 16 which is formed on the axis 18 of the blank and drill. This may be effected by having the sides of the groove 11 meet at a point far enough beyond the axis 18 to clear the core being formed; or, as is shown in Figs. 6 and 7, the drill may be provided with a central circular groove 25 to accommodate the core with the sides of the longitudinal groove 11 discontinued at the groove.

The dimensions of the groove 15 and the uncut core 16 may be varied to suit particular requirements, but generally the core should be of sufficient diameter and stiffness correlated with the depth of the groove 15 to aid in keeping the drill concentric with the axis of the relatively rotating

drill and wooden blank. I have found in practice that a core one-fourth the diameter of the bore, namely, with the core 16 one-fourth the diameter of the bore 3, is effective, with the depth of groove indicated in the drawings in guiding and causing the drill tip 9 to follow a straight rectilinear path, notwithstanding the direction of the wooden fibres and the slenderness and flexibility of the drills. The uncut core 16 is illustrated as of comparatively short but substantial depth. The drill itself is of very small diameter and in operation the outer free end of the core is gradually and progressively broken or twisted off, due to its small diameter.

In Figs. 8 to 11 I have shown somewhat diagrammatically a machine for drilling and boring blanks in accordance with my invention, this machine embodying novel and improved mechanisms for drilling deep, straight holes in wooden blanks for forming textile spools and bobbins and the like. The machine comprises a bed plate 30, having mounted thereon at one end a head stock 31 and at its other end a tail stock 32. Bridging these two stocks are a pair of outer guideway rods 33 and a pair of inner guideway rods 34. On the outer guideway rods 33 is mounted a drill carriage 35 and upon this carriage 35 are carried the drill chucks 36 and 37 which detachably carry the drills 2 and 4 respectively, set-screws 38 being shown for fastening the drills in their sockets or chucks. Compressed air is supplied in any suitable manner, as for example by means of the flexible pipe or hose 40 leading through suitable fittings 41 to passages formed in the chucks or sockets 36, 37 which receive the drills, the air pressure being supplied to the passages 10 of the drills. The carriage 35 is reciprocated along the guideway 33 by means of a mechanism including a pivot lever 44 pivoted to the bed at 44', the carriage and the lever being operatively connected together by a link 45 which is pivotally attached at 46 to the carriage and to the lever at 47. The lever 44 is provided with a number of openings 48 to provide for the adjustable attachment of the end 47 of the link 45 to the pivoted lever 44. The lever 44 is oscillated about the pivot point 44' by means of a crank shaft 49 suitably journaled in the tail stock 32 and having a crank 50 which operatively engages the lever 44. The driving connection between the crank 50 and the oscillating lever 44 consists of a sliding bearing block 51 which is pivotally fastened to the crank 50 and this block 51 is guided by and slides back and forth in an elongated slot 52 formed longitudinally of the lever 44. The pivot point 44' of the lever is below the axis of the shaft 49, and at the position of the drill carriage indicated in Fig. 8, namely, at the end of the return stroke of the drills, the pivoted lever 44 is to the left of the axis of the shank 49 and the bearing block 51 is disposed about midway the ends of the slot 52. Therefore, with the shaft 49 turning clockwise (Fig. 8) a relatively slow forward movement of the drill carriage 35 is produced and a relatively fast return movement is obtained, because in the former the operative connection between the crank and the lever 44 is nearer the outer end of the slot 52 and in the latter it is nearer the inner end thereof. The drive for the shaft 49 is diagrammatically illustrated, comprising the gear reduction mechanism 54 and a drive shaft 55.

In the particular embodiment shown the relative longitudinal movement between the drills and the blanks is produced by moving the drills

longitudinally by means of the reciprocating drill carriage 35, while the blanks are held longitudinally stationary in an intermittently rotated magazine 60, and the relative rotation is produced by maintaining the drills rotatively stationary and rotating the blanks on an axis including the axis of the drill. For this purpose the head stock 31 is provided with a pair of spindles 61 and 62 which are driven in any suitable manner, as for example by the belting indicated, and which are suitably journaled in the head stock 31, these spindles carrying at their inner ends adjacent the magazine 60 gripping chucks 61' and 62'. The chucks 61' and 62' are in line with the drills 2 and 4 and the arrangement is such that when the blanks disposed in the magazine 60 are pressed against these chucks the blanks are caused to rotate at a high speed. The chucks 61' and 62' are provided with recesses 64 and teeth 65 which function to bite into the end of the wooden blank to be bored when the blanks are pressed thereagainst. The blanks are brought into driving relation with the chucks 61' and 62' by means of a pair of reciprocating work support units 66 and 67 which are reciprocated back and forth along the guide rods 33 and 34, each work support being mounted on an outer rod 33 and the adjacent rod 34. Each of these work supports is provided with a bearing 66' and 67' in alignment with the drills and the chucks 61' and 62'. In these bearings are disposed guide bushings or sleeves 68 through which pass the drills to and fro in their reciprocating movements. On the end of each sleeve 68 there is journaled a chuck 69 having a conical recess 70. These journaled chucks 69 engage the blanks 1 when the work supports are moved forwardly to press the blanks against the driving chucks 61' and 62'.

The work supports 66 and 67 are independently biased in a direction to engage the blanks and force them against the driving chucks. In the particular embodiment shown, this biasing operation is obtained by means of weights 72 fastened by chains 73 fastened over pulleys 74 and attached to the work supports. The chucks of the work supports are automatically withdrawn from engagement with the blanks against the weights 72 by means of pull rods 75, which are fastened at one end to the drill carriage 35 and at the other end pass through openings formed in the work support uprights 76; and these pull rods 75 are provided with heads 75' which engage the uprights 76, when the drill carriage 35 nears its outermost position, to withdraw the work supports and their chucks from engagement with the blanks.

The magazine 60 consists of an intermittently rotatable frame journaled upon a shaft 80, the latter being carried in any suitable manner, as for example by the head stock 31, and this shaft 80 is in the horizontal plane of the drills and the chucks. The magazine frame consists of a sleeve journaled upon the shaft 80 and carrying end discs 81 and 82. These discs carry near their peripheries eight cylindrical receivers 83, these cylindrical receivers and carriers being intermittently alineable with the chucks and being shorter than the blanks in order that the chucks may engage the projecting ends of the blanks for rotating them. This magazine 60 is intermittently rotated one-eighth of a revolution at each complete reciprocation of the drill carriage 35. For this purpose the disc 82 is provided with a hub 82' having on the outer face thereof ratchet teeth 85 and a reciprocating pawl 86 is opera-

tively in engagement with the ratchet teeth 85, there being altogether eight ratchet teeth and this pawl 86 moving the magazine 60 through one-eighth of a revolution at each reciprocation. The pawl 86 is carried by one arm 87 of a bell-crank lever pivoted at 89 upon a bracket 90 carried by the machine bed. The other end 88 of the bell-crank lever is engaged and operated by an upright 76 which carries a finger 91 for that purpose, the finger 91 engaging the outer end of the lever 88 when the work support is actuated to the left (Fig. 8), which causes the upward movement of the pawl 86 and the movement of the magazine through one-eighth of a revolution. Upon movement of the work support to the right the bell-crank lever 87, 88 operates by gravity to cause the pawl 86 to engage the next lower tooth for the next intermittent operation. Any suitable means may be provided for preventing the over-travel of the magazine 60, namely, beyond the position to which it is actuated by the pawl 86. For this purpose I have shown a belt or rope friction means 93 disposed in a groove on the hub 81' of the end plate 81, one end of this belt or rope being attached to the frame and the other end having a suitable weight 94 attached thereto. This operates as a friction brake to prevent over-travel of the magazine.

A hopper 95 is shown for containing the charge of blanks 1 for drilling, the lower part of this hopper consisting of a receptacle 96 which holds a blank in alignment with the uppermost cylindrical receiver 83 of the magazine 60. The lowermost blank in the hopper 95 is automatically fed to the uppermost receiver 83 by means of a push rod 97 mounted in alignment with the receptacle 96 and the receptacle 83 and adjustably carried at one end by a bracket 98 carried from the drill carriage 35. The receptacle 96 being open at both ends the push rod 97 in each forward movement of the drill carriage 35 pushes the lowermost blank out of the receptacle 96 and into the uppermost receptacle 83 of the magazine. The blank which is being pushed into the cylindrical receptacle 83 automatically pushes out a drilled blank therein onto a trough 100. Cam or lining members 101 are mounted adjacent one end of the periphery of the magazine to engage the blanks disposed in the cylindrical carriers 83 to adjust the blanks automatically to a position wherein their ends will not foul the chucks.

As indicated above, each drill is supported by a butt or socket 41' to which the compressed air fitting 41 is attached, the set-screws 38 permitting the removal and replacement of drills. I prefer to make the drill tip 9 separate from the shank to avoid the necessity of drilling the relatively small air hole 10 the entire length of the drill. The tip may be brazed or welded to the shank. When the overall length of the shank does not exceed 12 inches I prefer to make the shank of a single piece of drilling rod, first drilling the air hole 10 and then forming the V-shaped chip channel on the side. With shanks longer than 12 inches I prefer to make them of steel tubing provided with the V-shaped channel.

It will thus be seen that the machine is entirely automatic. With the hopper 95 filled with blanks, at the first forward operation of the drill carriage 35 the push rod 97 pushes a blank from the hopper 95 into the uppermost cylindrical receptacle 83. At the first backward movement of the drill carriage 35 the magazine 60 is rotated one-eighth of a revolution and on the next forward stroke another blank is fed into the maga-

zine 60 and upon the next backward stroke the magazine 60 turns another one-eighth of a revolution, namely, to a position with the first supplied blank in line with the drill 2. The next forward movement of the drill carriage 35 results both in the supply of another blank to the intermittently rotated magazine 60 and on forward movement of the drill 2 to drill the middle section bore 3. Before the drill reaches the blank 10 the pull rod 75 which is carried by the drill carriage 35 releases the work supports 66 which then moves forward under the influence of the weights 72 to engage and line up the blanks disposed in the receptacles 83 in line therewith. The forward movement of the work support 66 also 15 presses the blank against its corresponding driving chuck 61', 62', whereupon the blank is rotated at a rapid speed while the drill 2 advances to form the bore. At each reciprocation thereafter 20 of the drill carriage 35 a blank is supplied to the magazine 60, the bore 3 is formed in a blank and the magazine 60 is advanced one-eighth of a revolution. When the blank formed with the bore 3 reaches the three-fourths position the drill 23 4 comes into operation to form the bores 5 and 6. This operation continues as long as the hopper 95 and the magazine 60 contain blanks to be drilled.

The flexing of the long slender drills is prevented according to the method of drilling above set forth. In the first drilling operation, which is performed by the drill 2, only the bore part 3 is formed, namely, a bore of one cross-section throughout and the boring is effected only at one 35 point throughout the length of the drill, namely, at the tip 9. Accordingly, the flexing of common practice, which I believe to be due in part to drilling two or more different sections simultaneously, is thereby prevented or minimized. Moreover, by forming the annular groove 45 slightly in advance of the bore 3 and the uncut core 16 and groove form a guide and directing means for the drill tip tending to keep it in a straight rectilinear line, namely, along the axis 45 of the blank and notwithstanding the particular fibrous character of the wood being worked upon. When the drill 4 is introduced into the bore 3 to form the smaller section bore 5, the guiding groove 15 and the uncut core 16 function to align and center this drill not only at the beginning of the operation but throughout the formation of the bore 5. The compressed air supply through the flexible pipes 48 continuously blows out the chips and cuttings and clears the end of the bore for fresh cutting operations.

I claim:

1. The method of drilling holes of relatively small diameter through elongated wooden blanks which consists in forming a bore of the desired diameter therein with no uncut core portion extending therethrough and simultaneously with the formation of the bore forming an annular

cylindrical-like groove with a short uncut core in the center thereof in advance of the bore throughout the drilling operation for guiding the drill in the rectilinear direction.

2. The method of forming a bore having sections of different diameters in elongated wooden blanks which consists in drilling one bore section part way through the blank and forming a central guiding core at the bottom thereof in one single operation and continuing the bore into a bore of smaller diameter by means of a drill whose shank and tip are of smaller diameter than that of the first bored section with said core guiding and positioning the drill of smaller diameter.

3. The method of forming a bore having sections of different diameters in elongated wooden blanks which consists in drilling one bore section part way through the blank in one single operation and continuing the bore into a bore of smaller diameter by means of a drill whose shank and tip are of smaller diameter than that of the first bored section and simultaneously reaming out the end of the first bore formed to form a bore of larger cross section than either of the other bores.

4. The method as set forth in claim 3 comprising the step of forming at the bottom of the first bore section part a centrally disposed core and annular groove for guiding the second drill.

5. The method of drilling holes of relatively small diameter through elongated wooden blanks which consists in forming a bore of the desired diameter therein with no uncut core portion extending therethrough and simultaneously with the formation of the bore, reaming the side thereof and forming and maintaining in advance of the bore throughout the drilling operation a central guiding core of short but substantial depth extending into the chip channel for guiding the drill in the rectilinear direction.

6. The method of drilling holes of relatively small diameter through elongated wooden blanks which consists in forming a bore of the desired diameter therein with no uncut core portion extending therethrough and simultaneously with the formation of the bore forming and maintaining a central cylindrical guiding core of short but substantial depth at the bottom of the bore throughout the drilling operation for guiding the drill in the rectilinear direction.

7. The method of forming a bore having sections of different diameters in elongated wooden blanks which consists in drilling one bore section part way through the blank and forming at the bottom thereof a centrally disposed core and annular groove therearound and continuing the bore into a bore of smaller diameter by means of a drill whose tip is of smaller diameter than that of the first bore section with said core guiding and positioning the drill of smaller diameter.

JOHN W. STOLLE.
